EGGLESTON SMITH, OF MAMARONECK, NEW YORK, ASSIGNOR TO EGGLESTON DRILLING CORPORATION, OF DOVER, DELAWARE, A CORPORATION OF DELAWARE

SELF-SEATING DEVICE FOR DRILLING BITS

Application filed September 27, 1926. Serial No. 137,840.

This invention relates to apparatus for earth-boring and particularly to apparatus for drilling wells for oil, gas, water and the like. The invention more especially concerns earth-boring apparatus of the rotary type in which the cutting or abrading of the material being drilled through, such, for example, as rock or mineral, is done by means of a rotary tool.

10 The object of the invention is to improve the construction of earth-boring apparatus of this character to the end that either small or large holes may be drilled with a greater degree of convenience, more expeditiously 25 and at less cost than hitherto.

In operating rotary drilling tools considerable difficulty has heretofore been experienced because of the refusal of the drilling bit to cut smoothly under certain conditions. 20 This difficulty has been encountered with steel bits of the so-called "fish-tail" type, as well as with steel bits having a relatively large number of cutting edges, and with abrasive bits. The refusal to cut smoothly has been 25 evidenced by a phenomenon known as "chattering" which is very destructive to both the bits and the driving mechanism. In carrying out certain rather extensive investigations 30 in the drilling of oil and water wells by means of the apparatus set forth in my copending application, Serial No. 712,197, filed May 10, 1924, I have discovered the reasons for this chattering, and have provided means or mechanism for eliminating it, which is the subject 35 matter of the present application.

My prior application just referred to relates to a device for connecting a drilling tool or bit made of abrasive material, such, for instance, as carborundum, with a drill stem 40 or drive pipe, by means of which the feeding pressure on the abrasive bit can be readily controlled, inasmuch as the weight of the drive pipe itself is removed from the bit, and the feeding pressure is supplied by applying 45 a predetermined force to the connecting device by means of weights of predetermined value or by other suitable means.

In drilling by means of the existing rotary methods, the bit is firmly secured to the drill 50 stem so that it moves as an integral part of

that stem. When drilling very shallow holes—that is holes in which the length of the drill stem is only a few inches beyond its last fixed lateral support—the axis of rotation of the drill essentially coincides with the axis 55 of the hole and the surface of the face of the bit coincides with the surface to be cut. As the depth of the hole increases and the drill stem lengthens beyond its last fixed lateral support, the axis of rotation of the drill 60 gradually deviates from the axis of the hole and the surface of the bit no longer coincides with the surface to be cut. This means that at any one time only a part of the surface of the bit is in contact with the surface to be cut. 65 The bit is canted to one side, increasing the pressure at the rim on that side and possibly raising the opposite side out of contact with the bottom. When the bit is so canted, instead of rotating about its central axis, it 70 changes its center of rotation and tends to turn about its point of support on the rim. The diameter of the hole even in the immediate vicinity of the bit is, however, somewhat larger than the diameter of the bit and 75 rotation can therefore take place for an instant and to a limited extent about the new center. The new rotation is stopped as soon as the bit strikes the side of the hole and rotation is then transferred back to the axis of 80 the bit for an instant while the point of support at the rim jumps forward to a new point of contact and support. The continued repetition of this procedure is, I believe, what 85 produces the chattering of the bit.

As the depth of the hole increases and considerable drill stem is added, another factor comes in which produces a deviation of the axis of the drill and drill stem from that of the hole being drilled and which augments 90 the tendency to chatter. In most drilling operations pressure is put upon the bit either by exerting pressure upon the upper end of the drill pipe or by allowing the drill pipe to rest upon the bit, or both, thus using the 95 weight of the pipe to obtain the necessary pressure to make the bit penetrate. No drill stem of substantial length, say 100 feet or more, is self-supporting on its base. It must lean over until it obtains lateral support from 100

the wall of the hole. When pressure is put upon the bit, the lower end of the stem leans over to the wall causing the axis of the drill stem to deviate from the axis of the hole, and 5 chattering is produced.

In accordance with my present invention, the undesirable effect of the leaning or canting of the drill stem is eliminated from the bit, i. e., it is prevented from being transferred to the bit. Accordingly the invention comprises a device for attaching the cutting tool to the rotary drill stem which is so constructed as to transmit to the bit the rotation of the drill stem but at the same time permit 15 the axis of the drill stem to deviate from the axis of the bit itself, or, in other words, from a line perpendicular to the surface being cut.

My invention will be better understood by referring to the accompanying drawings 20 which illustrate by way of example, several embodiments of the invention. In these drawings:

Fig. 1 is a vertical section of the lower end of a hole illustrating the general principles 25 of the invention;

Fig. 2 is a vertical section through the universal joint type of bit seating device which I now consider to be best adapted to carry out the invention;

30 Fig. 3 is a horizontal section taken on the line 2—2 of Fig. 2;

Fig. 4 is a vertical section of a modified form of bit seating device;

35 Fig. 5 is a bottom view of a device similar to the one shown in Fig. 4, but in which the bit is made in sections;

Fig. 6 is a vertical section taken on the line 6—6 of Fig. 5 illustrating the manner of 40 mounting the sections; and

45 Fig. 7 is a radial section taken on line 7—7 of Fig. 5.

Referring now to the accompanying drawings, and particularly to Fig. 1, in order that the general principles of the invention may 45 be more fully understood, the axis of the hole 10 which has been drilled by the tool or bit 11 is indicated by the line A. Line A is also the axis of the bit 11 which is perpendicular to the bottom 12 of the hole. The bit 50 11 is connected to the drill stem 13 by means of a universal joint 14 having its center of movement at the point 15.

The bit 11 is rotated through its connection with the rotary drill stem 13 by means of the 55 universal joint 14, but the construction of this joint permits the drill stem 13 to lean against the walls of the hole 10 for lateral support. As indicated in Fig. 1 an enlargement or guide 13' at the lower end of the drill stem is in contact with the wall of the hole at the point 16, and a drill stem 13 would also be shown in contact with the wall if Fig. 1 were extended upwardly a short distance. The purpose of the enlargement or guide 13' 65 will be explained below. The movement of

the drill stem 13 is not one of pure rotation but is a combined rotation about its own axis B and oscillation about the axis of the hole A, the axis B generating a long slender inverted cone the axis of which is the axis A of the hole.

The freedom of movement of the universal joint 14 which constitutes the attaching device, or self-seating device, of my present invention is sufficient to allow the drill stem 13 to obtain lateral support by leaning into contact with the walls of the hole, without transmitting the effect of this oscillation to the bit 11. The bit 11 therefore rotates smoothly with its entire cutting surface at all times in even contact with the bottom 12 of the hole, and without any tendency to chatter. The feeding pressure is substantially uniform over the entire area of the bit instead of being increased at the right hand rim or edge 80 17 as would be the case if the bit were rigidly secured to the drill stem. There is no tendency for the bit to cant to one side, raising the portion of its surface opposite the edge 17 out of contact with the bottom of the hole. 90

It is stated above that the axis "B" of the drill stem generates an inverted cone about the axis "A" of the hole. The maximum angle of deviation of the axis "B", i. e. the angle at the point of the cone, will determine the degree of freedom of motion to be provided by the universal joint, 14.

In drilling through hard formations, for which the present invention is primarily intended, although the rubbing of the sides of the bit produces a slight enlargement of the hole, there is no essential wear on the walls of the hole once the bit has passed. In practice that portion of the drill stem immediately above the universal joint which is referred to above as the enlargement 13' should be nearly the same diameter as the bit. This enlargement tends to act as a guide and prevent excessive leaning of the drill pipe which produces some tendency for the hole to deviate from a straight line. Above this enlargement the drill stem is bushed down to its normal diameter which is usually about one-half the diameter of the hole.

Turning now to Figs. 2 to 7 inclusive of the accompanying drawings, we will examine the construction of the self-seating device. In the form of self-seating device shown in Figs. 2 and 3, the upper or driving member 18 is threaded internally at 19 to the lower end of the drill stem or drive pipe 13. Member 18 telescopes within an outer or driven member 20, the fit between these two members being relatively loose as indicated by the space 21 since it is by the presence of this space that the lateral freedom of movement between the members 18 and 20 is allowed. The cutting tool or bit 22, which in this instance is a steel bit having cutters 23, is secured firmly to what is in effect the lower 130

end of the driven member 20, this lower end being of a composite or built-up construction for a purpose which will appear later.

The inner member 18 is provided on its exterior about mid-way between its ends with a cylindrical enlargement 25 preferably integral as may be seen in the cross section shown in Fig. 3. Enlargement 25 is provided with two oppositely disposed longitudinal key-ways 26, also shown in Fig. 3 and by means of a pair of keys which project inwardly from the interior surface of the outer member 20, the rotation of the driving member 18 is transmitted to the driven member 20. Aside from the keys 27 the interior of the driven member 20 is bored out as may be seen at 28 from its bottom upwardly to the tapering shoulders 29. This bore is to receive the enlargement 25 and it will be seen by referring to Fig. 2 that the space 21 is continued downwardly between bore 28 and enlargement 25 for the same purpose of providing freedom of movement between the outer and inner members of the joint. Spaces 30 are also provided on both sides of both keys 27, between the keys and the sides of the key-ways 26, for the same purpose. The sloping shoulder 31 and the upper end of enlargement 25 coat with the sloping shoulder 29 to prevent the outer member 20 from becoming disengaged from member 18.

The lower end of member 18 is turned down to form a shoulder 32 against which is fitted a hardened steel bearing ring 33 having a convex spherical surface 34, and a somewhat similar bearing ring 35 having a concave spherical surface corresponding to surface 34, is provided on the outer driven member 20. A plurality of balls 36 which are preferably held in place by the usual retainer (not shown) are provided between the bearing rings 33 and 35 for the purpose of transmitting the feeding pressure from the member 18 to the member 20 with the smallest possible amount of friction. Bearing ring 35 is retained within the bore 28 by means of a collar 36 which is internally threaded at 37 into the lower end of member 20. The drilling fluid passes downwardly through the drill pipe 13 and the interiors of members 18 and 20 to the apertures 39 provided therefor in the bit 22. Member 18 is extended below shoulder 32 in the form of a protecting skirt 38 which projects below the bearing rings for the purpose of keeping the drilling fluid away from the bearing rings. The bit is held in place by threads 40 on collar 36a. The same clearance as indicated previously at 21 is maintained between the outside of the skirt 38 and the interior of bearing ring 35 and collar 36. The outer member or shell 20 is of suitable length to appropriately guide the tool and prevent the

hole from deviating from a substantially straight line.

The spherical surfaces of bearing rings 33 and 35 have a common center at a point 41 which is near the top of the outer member 20, and by means of the pivotal bearing thus formed, and the loose fit all around between the various parts of members 18 and 20, the drill stem 13 will be permitted a limited freedom of movement and the device will operate as previously described in connection with Fig. 1.

Inasmuch as the space 21 allowed between the members 18 and 20 is sufficient to permit the passage of a considerable amount of drilling fluid, it is necessary to provide packing between the two members to resist this leakage and compel the fluid to flow to the bit. The packing consists of a ring 42 of resilient material such as rubber which is fitted against a shoulder 43 in the upper end of member 20 and held in place by a threaded holding ring 44. It will be noticed that ring 42 is placed opposite the center of oscillation 41 and the reason for this is to further reduce the friction between the two members of the joint by placing the packing where not only the minimum amount of motion, but also the simplest motion between the two members takes place. The vertical dotted lines proceeding from point 41 indicate the degree and direction of the movement of the axis of the member 18 with respect to the axis of member 20, and the horizontal dotted lines proceeding from point 41 indicate the extent of the relative vertical movement between the opposite surfaces of the two members which takes place as the result of the first movement.

The resilient packing ring 42 is held firmly in place by shoulder 43 and binding ring 44, but these parts are purposely constructed to cause ring 42 to project inwardly for a substantial distance 45 where the ring is unsupported at its sides. This allows the material of the ring 42 to yield sufficiently in the vertical direction to take up the movement indicated by the dotted lines entirely by the resiliency or give in the material itself, and without any slippage of the interior surfaces of ring 42 on the surface of member 18. By this construction the friction between parts 18 and 20 has been found to be reduced to a negligible amount so that with the friction reduced to this extent there is substantially no tendency for the oscillation of the drill stem to be transmitted to the bit and cause a tendency to chattering.

Although the bit 22 which has been shown in connection with the universal joint illustrated in Fig. 2 is a steel bit which is intended to drill a complete hole without leaving a core, it is to be understood that the device is advantageous to employ in connection with steel bits which are adapted to cut an annular hole so as to enable the taking of a core,

and that the device is also advantageous when treating with either solid or annular bits constructed of abrasive material.

Referring now to the modification shown in Fig. 4, the cutting tool or drilling bit here consists of an annular ring 46 of abrasive material, such for example as carborundum. This bit is therefore intended to cut an annular hole for the purpose of taking cores. The annular shank of the bit 46 is leaded into a metallic bit mounting 47 and this mounting is received within the lower end of an annular recess 48 formed in the bottom of a tool holder 49. The bit mounting 47 has an outer annular shoulder 47' at its upper corner, and the mounting is removably held within recess 48 by means of a plurality of pins 48' which are threaded through the outer wall of recess 48 and engage the shoulder. Tool holder 49 is a relatively massive annular steel casting which supports the various parts of the tool and by which the tool is secured to the drill stem. For this latter purpose, tool holder 49 is reduced at its upper end and threaded at 50.

Bit mounting 47 is provided with a series of guide rods 51 which are received within apertures 52 extending upwardly from the roof of recess 48. Bit mounting 47 and rods 51 slide freely in recess 48 and apertures 52 respectively, sufficient clearances being allowed to permit the axis of the bit 46 to cant slightly with respect to the axis of the tool holder 49. Springs 53, however, are provided on the pins 51 which tend to maintain the bit 46 in its extended position. When the tool holder 49 is attached to the end of the drill stem the flexible mounting of the bit 46 just described permits the drill stem to remain against the side of the hole without tilting or canting the bit 46; the rods 51 however transmit the rotation of the drill stem from the holder 49 to the bit. In this construction, however, the degree of friction is greater than with the universal joint shown in Fig. 2.

In the modifications shown in Figs. 5, 6 and 7 an abrasive bit is also employed but it consists of a plurality of separate sections 54 of carborundum, or other suitable material. These sections are independently mounted in a bit holder 55, which is in general similar to that shown in Fig. 4. The bottom of bit mounting 55, however, is provided with a plurality of radial slots 56 extending from the outer surface of the bit mounting inwardly and terminating short of the inner surface thereof. There is one slot for each carborundum section 54. The side walls 57 of these slots are tapering and therefore the slots are wedge shaped, and the slots have shoulders along the lower margins of their radial walls for the purpose of retaining therein the metal bit mountings 59 of the carborundum sections 54. The bit mountings are leaded to the bit sections 54 by means of the dove-tail construc-

tion shown in Fig. 6, and the mountings have guide rods 60 over which springs 61 are placed, and the rods 60 are received in radial slots 60' as indicated in Fig. 7. The purpose of the guide rod 60 is to act as a support for the spring 61 and to assist the bit mounting 59 in maintaining the bottom surface of the bit in flat position on the surface being cut.

The bit sections are assembled in the holder 55 by sliding the bit mountings laterally into the slots 56, the rods 60 entering the slots 60'. When the bit mountings are all in place in the several slots a collar 62 which is threaded upon the exterior of the mounting 55 is screwed downwardly to cover the slots 56 and hold the bit mountings therewithin.

I claim:

1. A self-seating device for earth-boring bits comprising a pair of telescoping driving and driven members, means for imparting rotation from one member to the other, and having coacting angularly disposed feeding pressure transmitting surfaces, said members fitting loosely together so as to permit a limited relative oscillation on said surfaces, and a packing ring mounted between said members to prevent the escape of drilling fluid from the interior of the inner member, said packing ring being composed of yielding material and supported on one of said members with its sides free to move longitudinally with respect to the members so that the relative longitudinal movement between the members is taken up by flexing of the material of the ring.

2. A self-seating device for earth-boring bits comprising a pair of telescoping driving and driven members, means for imparting rotation from one member to the other, and having coacting angularly disposed feeding pressure transmitting surfaces corresponding to tangents of arcs of the relative pivoted motions of the said surfaces, said members fitting loosely together so as to permit a limited relative oscillation on said angularly disposed surfaces, and a packing ring mounted between said members to prevent the escape of drilling fluid from the interior of the inner member, said packing ring being composed of yielding material and supported on one of said members with its sides free to move longitudinally with respect to the members so that the relative longitudinal movement between the members is taken up by flexing of the material of the ring.

3. A self-seating device for earth-boring bits comprising a pair of telescoping driving and driven members, the driving member being disposed within the driven member and provided at its lower part with a cylindrical enlargement, the outer member having an enlarged bore at its lower end for receiving said enlargement, a key-way extending longitudinally of said enlargement and a key coacting therewith projecting inwardly from

said bore, a pair of coacting feeding pressure transmitting surfaces mounted on said respective members, and means for securing a drilling bit to the outer member.

4. A self-seating device for well drilling bits comprising a pair of telescoping driving and driven members, the driving member being mounted within the driven member, means for transmitting rotation between said members, a pair of coacting angularly disposed feeding pressure transmitting surfaces mounted on said respective members, and a skirt mounted at the lower end of the driving member projecting downwardly below said coacting surfaces for directing the drilling fluid past said surfaces.

5. In an earth drilling apparatus, a rotary drill stem, a drilling tool, and a universal joint for securing the tool to the drill stem, said joint comprising driving and driven members keyed to one another in such a manner as to permit relative, limited motion between the parts, and said driving and driven members being provided with coacting angularly disposed annular surfaces for transmitting feeding pressure from the said drill stem to the said drilling tool.

6. In an earth drilling apparatus, a rotary drill stem, a drilling tool, and a universal joint for securing the tool to the drill stem, said joint comprising driving and driven members keyed to one another in such a manner as to permit relative, limited motion between the parts, said driving and driven members being provided with coacting angularly disposed annular surfaces for transmitting feeding pressure from the said drill stem to the said drilling tool, and allowing the axis of the drill stem to deviate from the axis of the hole.

7. A self-seating device for earth-boring bits comprising a pair of telescoping driving and driven members, means for imparting rotation from one member to the other, said members fitting loosely together so as to permit a limited relative oscillation of the driving and driven members, and packing means between said telescoping members for preventing the escape of drilling fluid from the interior of the inner member.

8. A self-seating device for earth-boring bits comprising a pair of telescoping driving and driven members, the driven member having an earth-boring bit secured to its lower end, means for imparting rotation from the driving member to the driven member, means for transmitting feeding pressure from the driving to the driven member at a point relatively near the bit to prevent disalignment of the hole being bored, said members fitting loosely together so as to permit a limited relative oscillation of the driving and driven members, and packing means between said telescoping members for preventing the es-

cape of drilling fluid from the interior of the inner member.

9. An earth drilling apparatus for deep well drilling comprising a rotary drilling bit, an elongated cylindrical bit carrying member closely fitting the hole being drilled and of sufficient length to properly guide the bit as it advances, a rotary drive shaft smaller than the hole being drilled and extending throughout the drilled portion thereof, and mechanism for operatively connecting said bit-carrying member to the drive shaft including means for permitting the axis of the bit to move angularly with respect to the axis of the drive shaft so as to allow the drilling bit to remain seated upon the surface being cut when the axis of the drive shaft diverges from the axis of the hole.

10. An earth drilling apparatus for deep well drilling comprising a rotary drilling bit, an elongated cylindrical bit carrying member having said bit mounted at its lower end and closely fitting the hole being drilled and of sufficient length to properly guide the bit as it advances, a flexible drive shaft smaller than the hole being drilled and extending throughout the drilled portion thereof, and mechanism for operatively connecting said bit-carrying member to said drive shaft to turn said member and apply feeding pressure thereto, said mechanism including means for permitting the axis of the bit to move angularly with respect to the axis of the drive shaft so as to allow the drilling bit to remain seated upon the surface being cut when the axis of the drive shaft diverges from the axis of the hole, and also including means for applying said feeding pressure at a point close to the lower end of said bit carrying member thereby applying feeding pressure without influencing the bit carrying member to deviate from drilling a straight hole.

11. An earth drilling apparatus for deep well drilling comprising a rotary drilling bit, an elongated cylindrical bit carrying member closely fitting the hole being drilled and of sufficient length to properly guide the bit as it advances, a flexible drive shaft smaller than the hole being drilled and extending throughout the drilled portion thereof, a driving member attached to said drive shaft and telescoped loosely into said bit carrying member so as to permit the axis of the bit to move angularly with respect to the axis of the drive shaft to allow the drilling bit to remain seated upon the surface being cut when the axis of the drive shaft diverges from the axis of the hole, said driving member coacting with the bit carrying member to turn the same and having a bearing near the bottom of said bit carrying member for transmitting longitudinal feeding pressure from the driving member to the bit carrying member thereby applying feeding pressure without influencing the

bit carrying member from drilling a straight hole.

12. An earth drilling apparatus for deep well drilling comprising a rotary drilling bit, an elongated cylindrical bit carrying member closely fitting the hole being drilled and of sufficient length to properly guide the bit as it advances, a flexible drive shaft smaller than the hole being drilled and ex-

10 tending throughout the drilled portion thereof, a hollow driving member attached to said drive shaft and telescoped loosely into said bit carrying member thereby permitting the axis of the bit to move angularly with respect

15 to the axis of the drive shaft so as to allow the drilling bit to remain seated upon the surface being cut when the axis of the drive shaft diverges from the axis of the hole, said driving member coacting with the bit carry-

20 ing member to turn the same, and a flexible packing between said drive member and said bit carrying member to confine drilling fluid therein.

13. An earth drilling apparatus for deep

25 well drilling comprising a rotary drilling bit, an elongated cylindrical bit carrying member closely fitting the hole being drilled and of sufficient length to properly guide the bit as it advances, a flexible drive shaft

30 smaller than the hole being drilled and extending throughout the drilled portion thereof, a driving member attached to said shaft and telescoped loosely into said bit carrying member, thereby permitting the axis of the

35 bit to move angularly with respect to the axis of the drive shaft so as to allow the drilling bit to remain seated upon the surface being cut when the axis of the drive shaft diverges from the axis of the hole, said

40 driving member coacting with the bit carrying member to turn the same, and a bearing near the bottom of said bit carrying member for transmitting longitudinal feeding pressure to said member from the driving

45 member, said bearing having coacting surfaces shaped to permit lateral movement of said surfaces with respect to each other so as to permit said angular movement of the bit carrying member to take place.

50 14. An earth drilling apparatus for deep well drilling comprising a rotary drilling bit, an elongated cylindrical bit carrying member closely fitting the hole being drilled and of sufficient length to properly guide the

55 bit as it advances, a flexible drive shaft smaller than the hole being drilled and extending throughout the drilled portion thereof, a driving member attached to said shaft and telescoped loosely into said bit carrying

60 member, thereby permitting the axis of the bit to move angularly with respect to the axis of the drive shaft so as to allow the drilling bit to remain seated upon the surface being cut when the axis of the drive

65 shaft diverges from the axis of the hole, said

driving member coacting with the bit carrying member to turn the same, and a bearing near the bottom of said bit carrying member for transmitting longitudinal feeding pressure to said member from the driving member, said bearing having curved coacting surfaces the center of curvature of which lies on the axis of the bit carrying member at a point near the top thereof.

15. An earth drilling apparatus for deep

70 well drilling comprising a rotary drilling bit, an elongated cylindrical bit carrying member closely fitting the hole being drilled and of sufficient length to properly guide the bit as it advances, a flexible drive shaft

75 smaller than the hole being drilled and extending throughout the drilled portion thereof, a driving member attached to said shaft and telescoped loosely into said bit carrying member, thereby permitting the axis of the

80 bit to move angularly with respect to the axis of the drive shaft so as to allow the drilling bit to remain seated upon the surface being cut when the axis of the drive shaft di-

85 verges from the axis of the hole, said driving member coacting with the bit carrying member to turn the same, and a bearing near the bottom of said bit carrying member for transmitting longitudinal feeding pressure to said member from the driving member,

90 said bearing having coacting curved surfaces the center of curvature of which lies on the axis of said bit carrying member near the top thereof, and a plurality of balls be-

95 tween said surfaces, thereby constituting a ball bearing for feeding pressure transmission.

In testimony whereof I affix my signature.
